EX

OF D 18,907

Design No. 18,907, dated February 5, 1889.

UNITED STATES PATENT OFFICE.

WILLIAM T. SMITH, OF PHILADELPHIA, PENNSYLVANIA,

DESIGN FOR A RUG.

SPECIFICATION forming part of Design No. 18,907, dated February 5, 1889.

Application filed January 11, 1889. Serial No. 296,110. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Rug, of which the following is a specification, reference being had to the accompanying photographic print, forming a part thereof, which conveys to any one skilled in the art of rug-weaving a clear understanding of the same, and is sufficient to enable such person to use my invention.

The photographic print shows but one-half of the rug. The half not shown is the repeat of that which is shown.

What I claim as my invention, and desire to secure by Letters Patent, is—

The design for a rug, consisting in the ornaments shown in the photographic print accompanying this specification.

WILLIAM T. SMITH.
